TELEPHONE SYSTEM

Filed Nov. 1, 1930

RUDOLPH FRANK STEHLIK,

By Chas. M. Candy, Atty.

UNITED STATES PATENT OFFICE

RUDOLPH FRANK STEHLIK, OF CHICAGO, ILLINOIS, ASSIGNOR TO ASSOCIATED TELEPHONE & TELEGRAPH COMPANY, OF CHICAGO, ILLINOIS

TELEPHONE SYSTEM

Application filed November 1, 1930, Serial No. 492,837, and in Great Britain November 5, 1929.

The present invention relates to telephone systems and is more particularly concerned with systems in which local or internal service is obtained automatically and facilities are provided for obtaining connection to a public main exchange from the same instrument. It has already been suggested to provide an instrument for use in a system in which both local and outside connections are obtained by dialling or the former by dialling and the latter with the help of an operator. The present invention is concerned with the case in which the local system is of the so-called intercommunication type, that is to say the wanted party is selected by pressing a particular button or equivalent operation rather than by dialling.

According to the invention the set is provided with the usual intercommunication push-button mechanism and also with a trunk key corresponding to each trunk line provided for out-service. Preferably also there is associated with each trunk line a visual indicator, for instance of the electromagnetic type, for indicating to all the stations when the trunk line is in use. The push button mechanism will preferably be arranged in known manner so that full depression of the button effects the signalling of the wanted station and that the button when released remains in a partially depressed position to complete the talking circuit, being fully restored only when the switch hook is operated on replacement of the receiver. Preferably also the trunk keys are interlocked with the push buttons in such manner that the operation of one key or button will release another previously depressed. In the case of the trunk keys, however, if a local push button is operated while a trunk key is depressed, the trunk key is only partially released and still maintains some of its contact springs in operated position. These springs are released subsequently when the receiver is replaced. In the circumstances just outlined, that is to say when a subscriber who has been speaking over a main exchange line wishes to refer to a subscriber accessible over the intercommunication system, the main exchange connection is held while this takes place and the speak-

ing circuit may then be transferred back to the main exchange line subsequently by the re-operation of the corresponding trunk key.

The invention will be better understood from the following description of one method of carrying it into effect which is given by way of example and should be taken in conjunction with the accompanying drawing.

In the system considered it is assumed that one or two particular stations are equipped for handling incoming main exchange calls by the provision of a bell permanently bridged across the trunk line in series with a condenser. The method of handling a call for a station not provided with such a bell would be that the station which replied to an incoming call on learning which party was required would signal that party over the intercommunication system and notify him that a call was awaiting him on the particular trunk line, whereupon he would press the corresponding trunk key and could then converse with the calling party as desired.

The station illustrated which is not equipped for the direct receipt of incoming main exchange calls comprises the usual transmitter T and receiver R which may be in the form of a handset and are electrically connected by means of the three-winding induction coil I arranged to give an anti-side-tone characteristic. The station is also provided with a dial having impulse springs IS and shunt springs SS for setting up main exchange connections while local connections are completed by means of the push button mechanism diagrammatically indicated at PB which may comprise a set of separate push-buttons or may be of the type in which a selecting knob is rotated to select the required station and then depressed. The signalling of the station is effected by means of a buzzer B operated by direct current. Trunk keys TK1 and TK2 are also provided corresponding to two main exchange trunks and these have associated with them visual signals V1 and V2 for indicating the engaged condition of the trunks. Of the springs controlled by the trunk keys the three upper sets marked S are restored to normal in case a push button is operated while the

trunk key is depressed, while the lower set marked H still remain operated and are only restored when the receiver is replaced. For each trunk four leads are multiplied between the various instruments the leads S1 and S2 associated with the first trunk being for signalling purposes while the leads T1 and T2 are the trunk conductors over which talking takes place. The intercommunication leads are multiplied throughout as usual as are also the battery leads—C+ and A+.

Study of the circuits will show that the station can only be signalled while the switch hook springs SH are in the normal position, a circuit being then completed over these springs and the individual multiple lead for the buzzer B. When the receiver is removed to reply to the call, the transmitter T receives current from the C battery over the switch hook springs and normal contacts of the trunk keys TK2 and TK1, the receiver circuit also including normal contacts of these keys. When the station shown calls on the intercommunication system, the depression of the appropriate button will connect the common terminal with the corresponding individual stud and also with the common ringing bar RB, thereby completing a circuit from the A battery for the buzzer of the wanted party.

In case the subscriber wishes to make a main exchange call, he will depress the trunk key corresponding to a trunk which is not in use, as indicated by the normal position of the associated visual signal, whereupon the intercommunication circuits will be disconnected and he will be connected through to a trunk over which he may set up his call by dialling in the usual manner. If during the course of either an incoming or an outgoing main exchange call he should wish to consult a local subscriber, he may press the corresponding push button whereupon the three upper sets of springs of the trunk key will be released thus connecting up the intercommunication speaking circuits while the main exchange connection is held over the lower set of springs, the various visual signals being also maintained operated. When he has concluded his local conversation and wishes to resume conversation with the main exchange subscriber, he will re-operate the trunk key thereby mechanically releasing the push button and restoring the trunk circuits.

According to the invention, therefore, a simple circuit arrangement has been designed whereby without undue complication local and main exchange service from the same instrument may readily be provided in connection with an intercommunication system and a main automatic exchange.

What I claim as new and desire to secure by Letters Patent is:—

1. In combination with a telephone instru-

ment of multi-station intercommunicating system normally connected for the extension of calls over such system, a manually operable element for selecting and signalling any other station of the system over a single wire speaking circuit, a two-wire trunk having a branch terminating in said telephone, and manually operable means for interrupting the normal connections to said telephone and for connecting the same to said trunk line.

2. In a telephone system, a telephone equipped with a combined station selecting and signalling mechanism for use in establishing local connections together with other equipment including a switching device for connecting said telephone with a trunk line extending therefrom to a distant exchange, means at said telephone and at the other telephones of such system for indicating the busy condition of such trunk, and means enabling a subscriber to set up a local connection while the trunk connection is held.

3. In a multi-station intercommunicating system, subscriber's instruments each provided with a combined station selecting and signalling mechanism for use in setting up local connections, a plurality of trunk lines extending from an outside exchange and having branches thereof terminating in the respective instruments of the intercommunicating system, keys in said instruments individual to said trunks and operable to complete incoming and outgoing connections thereover, and signals associated with said instruments for indicating the busy or idle condition of the respective trunks.

4. In a multi-station intercommunicating system, subscriber's instruments each provided with a combined station selecting and signalling mechanism for use in setting up local connections, a plurality of trunk lines extending from an outside exchange and having branches thereof terminating in the respective instruments of the intercommunicating system, keys in said instruments individual to said trunks and operable to complete incoming and outgoing connections thereover, and means enabling a subscriber to hold a trunk while a local connection to any other station of said system is being set up.

5. In a multi-station intercommunicating system, subscriber's instruments each provided with a combined station selecting and signalling mechanism for use in setting up local connections, a plurality of trunk lines extending from an outside exchange and having branches thereof terminating in the respective instruments of the intercommunicating system, keys in said instruments individual to said trunks and operable to complete incoming and outgoing connections thereover, means enabling a subscriber to hold a trunk while a local connection is being set up, means for enabling the subscriber called to then connect his instrument with such trunk.

6. In a telephone system wherein the telephones thereof are employed for both local and main exchange service; means manually rotated and then depressed to select, signal, and then connect a called station in talking relation with a calling station; trunk lines having branches terminating in the respective telephones of said system, a switching mechanism at each station manually operated to disconnect its associated telephone from the local system and to connect it to one of said trunk lines, visual signals at all stations also operated consequent to the operation of the switching mechanism of any station, and means enabling the reconnection forthwith of the calling station with the local system while the trunk busy signal indications are maintained. 70
7. In an intercommunicating system in which a telephone instrument has a switch arm which is rotated manually, after the removal of the receiver from the switchhook at the calling station, to a position individual to another desired station of such system, is then manually depressed to operate the called station signal and upon release moves to an intermediate position to complete a talking circuit to the called line and wherein, when the receiver is replaced, the said arm again opens the previously established talking circuit; the provision of a trunk line terminating in such instrument provided with a manually operable switching device of the type which when operated, after the removal of the receiver at such station, remains in its operated position until restored to an intermediate position by a subsequent operation of the local switch arm and which fully restores from its fully operated or intermediate position consequent to the replacing of the receiver upon its switchhook. 85
8. In an intercommunicating system, a telephone instrument, connections extending from said instrument to all others of the system, trunk lines each having a branch terminating in said instrument, manually operable circuit controlling keys for said trunk lines and for completing connections between said telephone instrument and others of the system; contacts effective upon operation of one of said keys, following the removal of the receiver from its switchhook, to disconnect said instrument from its normally existing connection with the system as employed in intercommunicating service and to connect said instrument with one of said trunk lines; signals at the respective instruments of the system operable by other contacts of said key to indicate at all stations that the trunk has been taken for use; means controlled by a subsequent operation of another of said keys, prior to the restoration of the receiver, to partially restore the first operated key and to complete a connection 130 to a local station while the specified trunk
- signal is maintained operated by the first operated key, the first operated key or a corresponding key at the called station being then optionally operated to again connect one of the other of the local instruments 80
- In testimony whereof I affix my signature.
